Application March 1, 1939, Serial No. 259,163
In Germany March 11, 1938

7 Claims. (CL. 179—18)

Often a series of special switching operations in the selector and the initiating of switching operations at other points of the connecting path are carried out by control devices for final selectors in automatic telephone systems which bring about the necessary switching operations for setting up and maintaining the connection between two subscribers' lines. The special control operations can be carried out in a comparatively simple manner by means of selectors which are provided with an auxiliary switch mechanism serving as a control switch. In the final selectors without control switches however the use of a more or less large number of auxiliary relays is necessary in order to carry out the particular control operations. The influence of the cost of these auxiliary relays and the economic running of the system can perhaps be left out of consideration as it is trivial. This, however, is not possible with reference to the complications in the circuit caused by the introduction of the auxiliary relays and the consequent difficulties in maintenance and testing of the installations. It is further obvious that the base plates of the set of relays can only take a certain number of relays so that often the necessary connection of the special auxiliary relays makes it necessary to use base plates of larger dimensions. As a rule this results in larger selector frames and a larger space is required for the whole installation.

The present arrangement relates to final selectors without control switches to which in addition to individual lines (subscribers' lines) lines directed to the groups, e. g. junction lines to other exchanges and to operators' positions, are connected and in which a selected connecting set can perform switching operations at points of the connecting path and the line which leads to the final selector. The object of the present invention is to make possible the preparing of all the necessary control operations for the various connection with the smallest possible number of relays in the final selector.

In order to obtain this result one winding of those differential relays which bring about switching operations in the connecting path, when the connection and an earth connection to a called set exists, is under the control of a testing device during the testing operation in the setting up of the connection and when a selected setting line is engaged, as well as when the whole direction lines of the group are engaged, brings into effect an engaged signal as this relay is prevented from operating by the local connection

of an opposite winding during the selection of a free line of a selected group.

In the drawings comprising Figures 1 and 2 a local telephone exchange is shown in which local, incoming and enquiry connections extend over the same final selector without control switches, to which, in addition to the individual line, groups of directed lines are connected.

It is understood that the invention is not limited to local exchanges but can be used in other installations in which individual lines and multiple connected lines can be reached over final selectors and the feeding bridge of the called subscriber is provided with a differential relay which on the connection of potential to the subscriber's set brings about switching operations at any desired points of the existing connecting path.

The drawings do not show all circuit details of the connecting devices and the connecting path but only those which are necessary in order that the control operations bringing about the switching through of the various relays connected according to the invention should be clearly understood.

I. LOCAL CONNECTION BETWEEN SUBSCRIBERS TN1 AND TN2

The call impulse transmitted when the calling subscriber $Tn1$ has removed his receiver brings about the setting of the wipers 1, 2 and 3 of the finder switch AS on the contacts 4, 5 and 6 in known manner and hence on the junction line of the calling subscriber's line $Tn1$. The cut-off relay operates in the test circuit and carries out known switching operations. The group selector GW is set by the first impulse train on the bank over which the final selectors are reached to which contact bank the junction line of the required subscriber $Tn2$ is connected. When the wipers 7, 8 and 9 reach the connection of a free final selector LW the following test and seizing circuit is completed: +, test relay not shown in the group selector GW, wiper 9, contacts 10, 11a1, 12klw, relay A1, winding III, —. In the group selector there follows in known manner the stopping of the operation, the switching through of the talking conductors, the disconnection of the impulse bridge and the locking of the seized final selector.

The relay A1 in the final selector LW operates in the seizing circuit. At contact 11a1 it opens the short circuit for relay C1 and it also opens the contact 13a1 in the circuit for the driving magnet of the final selector.

The relay C_1 operates. At contact $14c_1$ it prepares the testing circuit and at contact $15c_1$ the circuit of the vertical magnet H . At contact $16c_1$ the relay C_1 locks up independently of the off-normal contact $12klw$. Further it closes its contacts $17c_1$, $18c_1$, for a purpose to be indicated later and opens contact $19c_1$. Winding III of the relay A_1 is short-circuited at contact $16c_1$. The impulse and feeding bridge relay A_1 is not restored, however since its windings I and II are connected in the microphone feeding circuit of the subscriber's line Tn_1 .

When the calling subscriber sends out the impulse train for setting the final selector in a numerical impulse bank the impulses are transmitted to the vertical magnet H over contact $13a_1$: +, contacts $20p_2$, $21p_1$, winding I of relay V_1 , contacts $15c_1$, $13a_1$, $22u_1$, $23wlw$, vertical magnet H , -.

In this circuit the relay V_1 also operates and opens its contact $24v_1$ and at contact $25v_1$ short circuits its winding II so that it does not restore between the individual impulses. On the first vertical step of the final selector the contact $12klw$ is opened and hence the winding III of the relay A_1 is disconnected from the seizing circuit. The contact $26klw$ is closed and hence the switching over from vertical magnet H to the rotary magnet D is prepared.

After the coming into effect of the impulse train the relay A_1 remains energized for a long period. The contact $13a_1$ remains open. The relay V_1 restores. The relay U_1 is energized over: +, contacts $20p_2$, $21p_1$, $24v_1$, $23klw$, $17c_1$, winding I of relay U_1 , rotary off-normal contact $23wlw$, vertical magnet H , -. The vertical magnet H cannot operate in this circuit in view of the high resistance winding I of relay U_1 . At contact $22u_1$ the vertical magnet of the impulse contact $13a_1$ is disconnected and this is brought in connection with the rotary magnet D over the contact $27u_1$. The contact $28u_1$ is opened and hence premature connection of the rotary magnet D in a circuit bringing about the automatic movement of the selector is prevented. At contact $29u_1$ a holding circuit is prepared over the winding II of the relay U_1 which is necessary for the further selective setting of the final selector. The contact $30u_1$ serves to prepare the test circuit. By the opening of contact $31u_1$ a premature connection of winding II of relay B_1 is prevented.

The opening of contact $32u_1$ and closing of contact $33u_1$ serves to prepare the first call. The opening of contact $34u_1$ in the circuit of winding III of the relay B_1 has a purpose to be indicated later, not coming into consideration with the present connection.

The second impulse train serving to set the final selector on the junction of the numerical impulse receiver is transmitted to a rotary magnet D by means of the contact $13a_1$. In series with the rotary magnet D the control relay V_1 operates and at contact $35v_1$ closes the holding circuit of winding II of relay U_1 so that this relay remains energized after the opening of contact $23wlw$ on the first rotary step and interruption of the circuit over the winding I . The opening of contact $36v_1$ prevents the testing operation during the rotary movement of the final selector.

At the end of the rotary impulse train the relay V_1 restores. The test circuit is closed at contact $36v_1$. The holding circuit over winding II of relay U_1 is interrupted at contact $35v_1$. During

the release period of the relay U_1 the condition of the selected junction line (free or engaged) is determined.

Should the line be free then in view of the high resistance of the cut-off relay T_2 associated with the junction line only the test relay P_1 of the series test relays P_1 and P_2 operates: +, contacts $14c_1$, $30u_1$, $36v_1$, winding I and II of relay P_1 , relay P_2 , wiper 37 , contact 38 , relay T_2 , -.

The relay P_1 locks the selected junction line by short-circuiting its high resistance winding I at contact $39p_1$. It opens the contact $21p_1$, closes the contacts $40p_1$ and $41p_1$ in the feeding bridge, prepares at contact $42p_1$ the energizing circuit for the relay Z_1 coming into effect after the reply of the selected subscriber and at contact $43p_1$ closes a circuit for winding III of the relay V_1 -, contacts $43p_1$, $44z_1$, winding III of relay V_1 , contact $33u_1$, +.

The relay V_1 is energized so long as the slow relay U_1 holds its armature attracted after the free testing of its armature. At contacts $45v_1$ and $46v_1$ it short circuits the winding II of relays Y_1 and B_1 and at contact $47b_1$ disconnects the winding I of relay B_1 and at contact $48v_1$ connects the calling current source. The calling current flows over the following path: calling current, contacts $48v_1$, $40p_1$, winding I of relay Y_1 , contact $49p_2$, wiper 50 , contact 51 , subscriber's station Tn_2 , contact 52 , wiper 53 , contacts $45v_1$, $41p_1$, $46v_1$, $54p_2$, +.

After the release of relay U_1 the winding III of the relay V_1 is brought under the control of a time switch not shown by the opening of contact $33u_1$ and closing of contact $32u_1$ and is connected at particular intervals e. g. every 5 seconds. The relay V_1 is energized.

After the selected subscriber replies in a call pause the relay Y_1 operates but not the differential relay B_1 which is also in the feeding bridge. The contact $55y_1$ is opened. At contact $56y_1$ the switching through relay Z_1 is connected and at contact $57z_1$ locks up in a circuit independent of contact $56y_1$ and at contacts $58z_1$ and $59z_1$ switches through the talking conductors. The contact $44z_1$ in the circuit for winding III of relay V_1 is opened and in this way influences the winding of the control switch.

The two subscribers Tn_1 and Tn_2 are connected with one another. When at the end of conversation the calling subscriber hangs up his receiver the relay C_1 is short circuited at contact $11a_1$. It restores, however, and at contact $14c_1$ opens the circuit of the relays P_1 and T_2 . The feeding circuit for the subscriber Tn_2 is interrupted at contacts $40p_1$ and $41p_1$. The final selector LW_1 is brought to its normal position. This is done in such a manner that in the first place the rotary magnet D of the final selector energizes over: +, contacts $20p_2$, $21p_1$, $24v_1$, $26klw$, $19c_1$, $28u_1$, rotary magnet D , -. Over the contact $60d$ the winding II of relay U_1 operates and opens the circuit of the rotary magnet D at contact $28u_1$. This magnet restores. The alternate play between the rotary magnet D and the relay U_1 is repeated until the wipers of the contact bank have dropped down to their lowest position. The rotary off-normal contact $26klw$ is then opened so that the rotary magnet D cannot take up any further impulses. The final selector then reaches its normal position.

The release of the relay C_1 brings about the release of the preceding selector since it is dis-

connected from the incoming seizing conductors by the opening of contact 16c1.

When the junction line of the selected subscriber $Tn2$ is engaged when the final selector sets on it the relay $P1$ cannot operate. This has the result that after the release of the control relay $U1$ also determining the test period, a circuit is completed over winding II of relay $B1$: +, contact 54p2, winding II of relay $B1$, resistance 61, contacts 31u1, 62wh, 63p1, -. The relay $B1$ by closing the contact 64b1 connects the engaged signal to the winding III of the relay $A1$. The calling subscriber hears the engaged signal and hangs up.

The reversal of the direction of feeding current for the calling subscriber occurring on the opening of contacts 65b1 and 66b1 and closing of contacts 67b1 and 68b1 is not important for the present connection.

II. CONNECTION OVER A LINE OF A GROUP OF LINES IN THE SAME DIRECTION

Groups of direction lines are connected to the final selector; it is assumed that there are two groups of which the two lines $VL11$, $VL12$, $VL21$ are engaged. After the setting of the final selector corresponding to the characterizing digit of the required group the selector is automatically set on the first free line independently of which group has been selected. The further switching operations in the final selector depend upon whether the line group $VL11$, $VL12$, or the line group $VL21$, $VL22$ has been selected.

While the further setting up of the connection is carried through in the same manner as in the selection of an individual line by the setting of the final selector on a free line of the groups $VL11$, $VL12$, a switching operation takes place in the final selector on the seizing of the free line of the groups $VL21$, $VL22$ by which all sections connected with the talking conductors are disconnected. A continuous metallic connection is set up between the contacts of the group selectors and the wipers of the final selectors.

1. Connections with a junction line of group $VL11$, $VL12$

After the selection of that bank in which the junction lines $VL11$, $VL12$ are included or after the setting of the wiper in the final selector on the contact of the first junction line $VL11$, the general contact 79sk is closed.

If the junction line $VL11$ is free then in the same way as described in section I the test relay $P1$ is effective after the release of relay $V1$ and initiates the completion of the connection.

If the junction line $VL11$ is engaged the relay $P1$ cannot operate. After the release of the control relay $U1$ determining the test period, the engaged signal must not be connected yet however, in contrast to the case of a connection with a guarded individual line, since the engaged condition of the other lines of the groups must first be determined. For this purpose after the release of relay $U1$ over contact 79sk a winding III of relay $B1$ is connected: -, winding III of relay $B1$, contacts 34u1, 10sk, 26klw, 24v1, 21p1, 20p2, +. At the same time over contact 31u1 the circuit over winding II of relay $B1$ is also completed: -, contacts 63p1, 62wh, 31u1, resistance 61, winding II of relay $B1$, contact 54p2, +. The winding III is an opposite winding to the winding II. The effects of the current flow-

ing through both the windings cancel out. The relay $B1$ does not operate.

The rotary magnet D is connected: -, rotary magnet D, contacts 28u1, 10 sk, 26klw, 24v1, 21p1, 20p2, +. The rotary magnet D connects the winding II of relay $U1$ at contact 60d which interrupts the circuit of the rotary magnet D. The alternate connection and disconnection of D and $U1$ continues until the test wiper 37 reaches the test contact of the junction line $VL12$. The relay $P1$ operates in the test circuit extending over contact 71 and the cut-off relay $T12$. In the same way as with the connection to a single line, since the cut-off relay $T12$ has a high resistance, the test relay $P2$ does not operate in the present connection also. At contact 21p1 the circuit for the rotary magnet D and the winding III of the relay $B1$ is interrupted. At contact 63p1 the circuit over the winding II of relay $B1$ is opened.

The further setting up of the connection takes place in the same way as described in Section I.

If all junction lines of the group $VL11$, $VL12$ are engaged the final selector is stepped onto the contact set of the last junction line since then the general contact 70sk is open. The rotary magnet is no longer energized. The circuit of winding III of relay $B1$ is interrupted. Relay $B1$ operates over its winding II and connects the engaged signal as in Section I.

2. Connection with a junction line of groups $VL21$, $VL22$

The cut-off relays $T21$, $T22$ and the junction lines $VL21$, $VL22$ have a lower resistance than the cut-off relays $T1$, $T2$, $T11$, $T12$ of the remaining lines connected with the final selector. On the setting of a final selector on the junction line $VL21$, $VL22$ the test relay $P2$ also operates therefore. In known manner, it disconnects in the final selector all devices which are in connection with the talking conductors and completes a continuous metallic connection between the incoming talking conductors and the wipers 50 and 53 of the final selector. By the opening of contacts 73p2 and 74p4 there follows the disconnection of the bridge relay $A1$, by the opening of contact 49p2 the disconnection of winding I of relay $Y1$ from the wiper 50, by the opening of contact 54p2 the disconnection of the positive pole of the winding II of relays $B1$ and $Y1$ and by the closing of contacts 75p2 and 76p2 the direct metallic connection of the conductors outgoing from the contacts of the group selector with the wipers 50 and 53 of the final selector.

In the same way as with connections to a junction line of groups $VL11$, $VL12$, in connection with the junction lines $VL21$, $VL22$ also, after the setting of the selector on the first junction line $VL21$, when the same is engaged on energizing of the relay $B1$ for the purpose of transmitting the engaged signal is prevented. Over the general contacts 70sk and contacts corresponding to these, the reverse winding III of the relay $B1$ is connected. When the free junction line $VL22$ is reached the test relays $P1$ and $P2$ are energized and open the circuit of the rotary magnet D at the contacts 20p2, 21p1, and the winding III of relay $B1$ as well as the circuit for winding II of relay $B1$ at the contacts 63p1 and 54p2.

When all the groups $VL21$, $VL22$ are engaged and the selector reaches the contact set of the final selector of the group, the contact 70sk or a contact corresponding to this is open. The wind-

ing III of the relay **B1** is disconnected. The relay **B1** then operates due to current flowing over its winding II and connects the engaged signal.

III. OUTGOING EXCHANGE CONNECTIONS

After the setting of the finder switch **AS** on the junction line of a calling subscriber **Tn1** and transmission of a characterizing digit for exchange connections, the group selector **GW** sets on the free exchange line **VL_a**. In the test circuit over the wiper **9**, the contact **80** and the conductor **81** the relay **C2** operates and closes a circuit over the relay **C3** and the winding I of the relay **X2** at contact **100c2**. The relay **X2** by opening the contact **101x2** prevents the energizing of the relay **X1** over its winding III after the closing of the contact **102c3**. The call relay **A2** is connected and at contact **104c2** the upper talking conductor of the exchange line **VL_a** is switched through. In bridge to the access means, reached over the group selector **GW**, to the talking conductors of the exchange line **VL_a** are the relays **S1** and **X1**. The relay **X1** is a differential relay and it is not operated in the microphone feeding circuit. The relay **S1** only is energized. Among other things it closes the contact **105s1** in the exchange line.

The relay **C3** connected by relay **C2** in the seizing operation connects the winding I of relay **L** over its contact **106c3**, which contact **107l** connects the winding II of relay **X2** in parallel to the condenser **108**, which however is not important for the moment.

Between the conductors **110** and **117** of the exchange line **VL_a** the following direct current bridge exists: conductor **110**, contacts **111as1**, **105s1**, **104c2**, **112s2**, repeater winding **113**, contact **146x2**, winding II of relay **L**, repeater winding **114**, contacts **115s2**, **116as1**, conductor **117**. By means of this rectifying bridge the call impulse is transmitted in the known manner to the remote exchange and controls the call device therein.

Over the winding II of relay **L** the current flows in such a direction that it increases the effect of the current over the locally connected winding I. The energized condition of relay **L** is therefore not effected.

The impulse train sent out from the calling subscriber for setting a selector in the remote exchange is transmitted from the bridge relay **S1** by means of the contact **105s1**.

IV. SETTING UP OF AN ENQUIRY CONNECTION

The enquiry connecting relay group which consists of the relays **Z2** and **Y2** is connected to relay **C3** in preparation by means of contact **118c3**. The energizing and holding circuits of relay **U2** and **U4** which are operated on the switching over and exchange connection are prepared at contact **119c3**.

For the purpose of setting up an enquiry connection the calling subscriber **Tn1** momentarily operates the enquiry key **RT1** at his apparatus and thereby connects earth to the talking conductor. The differential relay **X1** operates, and the feeding bridge relay **S1** remains energized. At the contact **120x1** the circuit over the winding I of relay **Z2** is completed: +, contacts **118c3**, **121y2**, winding I of relay **Z2**, contacts **120x1**, **122u4**, **123u3**, -. Relay **Z2** closes the contact **124s2** so that it prepares to lock up over winding II and prepares an energizing circuit over the winding I of relay **Y2**. As long as the contact **120x1** is completed the last mentioned two windings are short circuited. At contact **125s2** the choke **D1** is connected in bridge between the con-

ductors **110** and **117** and the exchange line **VL_a**. The contacts **112s2** and **115s2** are opened and contacts **126s2** and **127s2** are closed. The part of the exchange path connected with the exchange subscriber **Tn1** is disconnected thereby from the outgoing exchange line **VL_a** and connected to the enquiry path **RL**.

By the release of the key **RT1** and disconnection of earth the differential relay **X1** restores again. The contact **120x1** is opened. The short circuit of the winding I of **Y2** and II of **Z2** is removed. The relay **Y2** operates: +, contacts **118c3**, **121y2**, windings I and II of relay **Z2**, winding I of relay **Y2**, contacts **124s2**, **122u4**, **123u3**, -. The contact **128y2** is closed and thereupon the contact **121y2** is open. The following holding circuit now exists for relays **Y2** and **Z2**: +, contacts **118c3**, **128y2**, winding II of relay **Y2**, winding II of relay **Z2**, winding I of relay **Y2**, contacts **124s2**, **122u4**, **123u3**, -.

At contact **129y2**, the energizing circuit for the relay **U2** of the switch relay group is further prepared. The relay **U2** does not operate since the relay **L** is energized and the contact **130l** is open.

At contact **131y2** a conductor of the enquiry path **RL** is switched through so that now since the contact **132s1** is also closed, the call relay connected to the conductors **84** and **85** of the local network is operated. A free finder switch **AS** sets on the enquiry line. The enquiring subscriber **Tn1** sets the group selector **GW** and the final selector **LW** on the subscriber required in the enquiry connection.

The circuit of the relay **A1** in the final selector exists as follows after the seizing of the final selector and during the whole enquiry connection: -, winding I of relay **A1**, contacts **65b1**, **73p2**, wiper **7** of **GW**, **1** of **AS**, contact **83**, conductor **84**, contacts **133u4**, **126s2**, repeater winding **113**, contact **146x2**, winding II of relay **L**, repeater winding **114**, contact **127s2**, **131y2**, **132s1**, **134u4**, conductor **85**, contact **86**, wiper **2** of **AS**, **8** of **GW**, contacts **74p2**, **66b1**, winding II of relay **A1**, +.

In this circuit the current flows over the winding II of relay **L** in such a direction that it does not remove the effect of the current flowing over the locally connected winding I. The relay **L**, therefore, remains energized.

The setting of the final selector takes place in the manner described in Section I.

V. TAKING OVER OF THE EXCHANGE CONNECTION BY THE SUBSCRIBER **Tn2**

In the feeding circuit of a called subscriber **Tn2** the windings I and II of relay **Y1** are included and the windings I and II of the relay **B** connecting the engaged signal when a selected individual line is engaged or after the testing of the lines of a group which are all guarded. The windings I and II are connected differentially so that the relay **B1** is not energized over the feeding circuit. The winding II is the same winding as is connected when the relay must operate in order to give out the engaged signal.

For the purpose of taking over the exchange connection in conjunction with the enquiry conversation with the subscriber **Tn1**, the subscriber **Tn2** must press momentarily the key **RT2** on his apparatus. As a result earth is connected to the lower talking conductor. The windings II of relays **Y1** and **B1** are short circuited. The relay **Y1** remains energized over its winding I. Relay **B1** operates. The closing of contact **64b1** is without effect since the contact **55y1** in series with it is open. The contacts **65b1**, **66b1** are opened

and the contacts 67b1, 68b1 are closed. There follows a reversal of the direction of current flowing over the enquiry path since the winding I of relay A1 connected over negative potential is transferred from the upper talking conductor to the lower and the winding II connected with positive potential is transferred from the lower talking conductor to the upper. The result is that the direction of current over the winding II of relay L (Fig. 2) is changed so that the effect of the current over winding II cancelled out that of the current over winding I.

The relay L restores and at contact 1301 closes the energizing circuit over winding I of relay U2: +, contacts 119c3, 1301, 129y2, 135u3, winding I of relay U2, -. At contact 136u2, an energizing circuit is prepared over the winding I of relay U3 which however again operates so long as its winding together with its winding II of relay U2 is short-circuited at contact 1301. By the opening of contact 137u2, 138u2, and closing of contacts 139u2, 140u2, the calling subscriber Tn1 is disconnected from the exchange line VLa and this line is connected over the conductors 84 and 85 of the enquiry path. There is no effect on the current flowing over the enquiry path to the winding II of relay X2 since the contact 1071 is open.

On the release of the key RT2 of the subscriber's set Tn2 the relay B1 sets back its contacts to their normal positions shown in the drawings thereby altering the direction of the current over the enquiry path again and over the winding II of relay L. The windings I and II act together so that the relay L operates, the contact 1071 is closed and the contact 1301 is opened.

At contact 1071 the winding II of relay X2 is completed. The current flowing over its winding has such a direction that it increases the effect over the locally connected winding I. The relay X2 therefore remains energized.

At contact 1301 the short circuit for the winding II of the relay U2 and I of relay U3 is removed. The relay U3 operates, disconnects the winding I of relay U2 at contact 135u3, connects the winding of relay U3 at contact 141u3 and a slow-to-operate relay U4 at contact 142u3. By the opening of contact 123u3 the holding circuit over the relays Y2 and Z2 is opened and at contact 143u3 a later energizing of this relay is prepared. The release of relay Y2 and Z2 results in the opening of contact 131y2 in the enquiry path and of contact 129y2 in the energizing circuit of the winding I of relay U2. The disconnection of the enquiry line RL from the exchange line VLa results from the opening of contacts 126z2, 127z2 and the switching through of the exchange line takes place at contacts 112z2 and 115z2. The choke Dr1 is disconnected by the opening of contact 125z2.

The subscriber Tn2 taking over the connection is now connected over the final selector, group selector, and conductors 84 and 85 with the left hand winding of the repeater Ue to the exchange line VLa. This switching over of the exchange connection to the exchange line is performed by the relay B1 arranged on the other set of the connecting path at the final selector and this relay transmits the transferring impulse sent out by the subscriber by reversing the current direction in the enquiry path. The relay B1 is that relay which when an individual line is engaged or all lines of a selected group are engaged connects an engaged signal.

On its operation relay U4 opens the contact 122u4 and at contact 144u4 finally prepares the energizing circuit over the winding I of the relay Z2. By the opening of contacts 133u4, 134u4 and the closing of the contacts 145u4, 146u4 the enquiry switching over point and the enquiry line RL extending through the local exchange are connected by means of the contacts 137u2 and 138u2 of the part of the exchange connecting path from the present exchange connection in order that over this part of the exchange connection an enquiry connection can eventually be set up again.

15 VI. SETTING UP AN ENQUIRY CONNECTION ON THE PART OF THE SUBSCRIBER Tn2

If the subscriber Tn2 who has taken over the exchange connection from the subscriber Tn1 wishes to make an enquiry connection he momentarily presses the key RT2. By means of the earth connection the differential relay B1 is again energized and transmits the enquiry impulse to the exchange line and here brings about the corresponding operation of the enquiry switch relay group. The differential relay B1 in known manner reverses the direction of the current flowing over the conductors 84 and 85. This current reversal operates on relay X2 in such a manner that current now flows over the winding II in the opposite direction to that flowing over the winding I. Relay X2 restores and at contact 101x2 connects the winding III of the relay XI: +, winding III of relay XI, contacts 101x2, 102c3, 100c2, -. Relay XI operates and contact 120x1 closes the energizing circuit already described over winding I of relay Z2.

The relay Z2 operates. On the release of the key RT2 and release of the relay B1 the direction of current over the conductors 84 and 85 is again reversed. The relay X2 operates again. The relay XI restores. The relay Y2 operates. The enquiry switching operation is now performed under the control of the final selector and also the engaged signal is connected by the relay B1 serving to lock the selected line. The subscriber can set up the enquiry connecting path.

VII. TAKING OVER THE ENQUIRY CONNECTION BY THE SUBSCRIBER CALLED IN THE ENQUIRY CONNECTION

50 If the subscriber called in this enquiry connection wishes to take over the exchange connection again he operates his enquiry key since the subscriber was selected in the same manner as the subscriber Tn2 over a final selector. The B-relay associated with the final selector in use is energized. This effects the current reversal in the connecting path and a release of the relay L. In contrast to the procedure described in Section V since the switching relays U2 to U4 are energized this relay must be restored. This is carried out by the short circuiting of winding I of relay U3 at contact 1301 and of winding II of relay U2. Relay U2 restores. The contacts 136u2, 139u2, and 140u2 are opened and the contacts 137u2 and 138u2 are closed. The enquiring subscriber Tn2 is disconnected. Relay U3 still remains energized over its winding II and maintains the relay U4 connected as a result at contact 142u3. The alterations of the current direction occurring during the presence of the key do not affect the winding II of relay X2, since the contact 1071 is open.

After the release of the key at the call subscriber's set the relay B at the final selector is operated. Relay L operates and at contact 1301

opens the holding circuit over the winding II of relay U3. The relay U3 restores and also disconnects the relay U4 which by opening contacts 145u4 and 146u4 as well as by closing the contacts 133u4 and 134u4 brings about the restoration of the enquiry path to its normal position shown in the drawing. The release of relay U3 also results in the disconnection of the enquiry switching relay group since the contact 143u3 is opened. Relays Y2 and Z2 restore and switch through the exchange line.

VIII. INCOMING EXCHANGE CONNECTION

In a call over the exchange line VL_a the call relay A2 is energized by means of the call current connected to the calling exchange. It connects the holding relay Hr1: +, contacts 150c2, 151a2, relay Hr1, contacts 152s1, 153as1, -. The relay Hr1 locks up at contact 154hrl independently of contact 151a2 and at contact 155hrl closes the circuit of the call lamp AL1 associated with the exchange lamp VL_a.

The operator takes up her instrument whereby the contact 155hu is closed. She operates the enquiry switch AT1 of the exchange line VL_a and thereby energizes the connecting relay AS1 over the contact 156. The relay AS1 prepares a holding circuit for itself at contact 157as1 and opens the contacts 111as1, 116as1 and by closing the contacts 158as1 and 159as1 connects the talking apparatus of the operator in bridge between the conductors 110 and 117 of the exchange line VL_a. By the opening of the contacts 174as1, 175as1 and closing of the contacts 170as1, 169as1 the relay Dr3 is bridged across the conductors 176 and 177 with its winding II and III. Since the local line and the local network is bridged in the same way as the subscriber's line the call relay associated with the exchange line of the local network operates and brings about the setting of a finder switch on this line. The relay Dr3 is energized in the circuit extending over its winding II and III and the circuit over its lamp BL1 at contact 180dr3 is opened.

The operator makes an enquiry and finds the requirement of the calling subscriber. Thereupon she restores the enquiry switch to its normal position. The relay AS1 remains energized over its contact 157as1 and the contact 160 of the enquiry switch AT1. The connecting key VT is now depressed momentarily and the relay V4 energizes: +, contacts 155hu, 160, 161, relay V4, -. The relay V4 locks up at contact 162v4 independently of contact 161 of the connecting key VT. By closing the contact 163v4 it connects the choke Dr2 in bridge across the branch of the exchange line VL_a. By the opening of the contact 164v4 the choke Dr4 is disconnected. The talking apparatus of the operator is disconnected together with the impulse contact nsi by the opening of contacts 165v4, 166v4 and the closing of contacts 167v4, 168v4 from the exchange line VL_a leading to the remote exchange and connected to that branch of the exchange connecting path which is connected with the local network over the contacts 169as1 and 170as1. There follows further by the opening of contacts 171v4 and closing of contacts 172v4 a switching over of the relay Dr3 and by the connection of the impulse contacts nsi the setting up of an impulse circuit for setting the selector of the local network. At contact 178v4 the winding I of relay Dr3 is disconnected.

When the operator operates her dial switch in order to set the selector in its home position the 75

contact nsa is closed during each operation. The relay E operates and during the impulse short circuits at contact 173e both windings II and III of relay Rr3. The relay Dr3 remains however energized over its winding I connected at contact 178v4. At the completion of each digit selection the relay E restores and removes the short-circuit again from the windings II and III.

If the selected junction line e. g. to the subscriber Tn2 is engaged or if all junction lines VL11, VL12 and VL21, VL22 in the required traffic device are guarded then as described in Section I and II after the selection of the subscriber lines or after the testing of all the junction line of the selected group the relay B1 in the final selector is energized by the closing of a circuit over its winding II. By the opening of the contacts 65b1, 66b1 and the closing of the contacts 67b1, 68b1 it reverses the direction in the circuit over the windings II and III of relay Dr3. The effect of the current over these windings now opposes the current over winding I. The relay Dr3 restores and at its contact 180dr3 connects the busy lamp BL1, so that the operator has a visible indication that the selected subscriber as all the lines of the selected group are engaged. At the same time there follows in the final selector a connection of the engaged buzzer to winding III of the relay A1 so that the operator also receives the audible indication as well as the visible one.

The relay B1 associated with the final selector always carries out the same switching over on the coming into effect of an impulse transmitted from a junction point for initiating an enquiry switching over or to switch over an exchange connection and also to register the engaged condition of the selected line. It always reverses the direction of the current leading to the final selector. This current reversal always effects the transmission to the exchange line and thereby in dependence upon its condition effects either the switching over required by the junction line or the connection of a visible engaged signal.

What is claimed is:

1. In a telephone system, three lines, an automatic switch having access to one of said lines, means for operating said switch to said one line at different times to extend connections thereto from a second of said lines, means in said switch effective during the extension of such connections to test said one line and complete the connections thereto only if said line is idle, a busy relay controlled by said last means and operated thereby whenever the line tests busy to transmit a busy signal, means for operating said relay at times over said one line after a connection has been completed thereto from said second line over the switch, another switch having access to the third of said lines, means controlled by said relay upon said operation thereof over said first line to hold the connection from said second line and seize said other switch, and means for then operating said other switch over said first line to extend a connection to said third line while the connection from said second line is maintained.

2. A telephone system as claimed in claim 1, wherein said first automatic switch and said other switch are identical.

3. In a telephone system; three lines; means operated to complete a connection between two of said lines; means thereafter controlled by a subscriber over the first of said two lines for extending an enquiry connection to the third line while holding the connection to the second

of said two lines; said last means including an automatic switch having access to said third line, means controlled over said first line to operate said switch to prepare the enquiry connection to said third line, means in said switch for then testing said third line, a relay operated by said last means if said third line is busy to cause a busy signal to be transmitted over said first line, and means in said switch operated to complete the enquiry connection to said third line if same tests idle; subscriber controlled means for thereafter operating said relay over said third line; and means controlled by said relay upon such operation thereof for transferring the enquiry connection to said connection to said second line, thereby to interconnect said second line and said third line for conversation.

4. A telephone system as claimed in claim 3, wherein said first means includes an automatic switch identical to said switch having access to said third line.

5. In a telephone system, a rotary connector switch having access to individual lines and groups of lines, means for seizing said switch and operating it either to an individual line or to a group of lines, means for testing an individual line if said switch is operated thereto, said last means effective also to test the lines of a group successively if the switch is operated to that group, a relay having a pair of opposing windings, one of said windings being controlled by said testing means and energized if the tested line is busy, means for energizing the other of said windings only during the testing of group lines thereby to prevent the operation of said relay over said one winding whenever a line in the tested group tests busy, said relay operating over said one winding when an individual line tests busy or after all of the lines of a group have been tested and found busy, and means controlled by said relay upon such operation thereof for transmitting a busy signal.

6. In a telephone system, an automatic switch, lines accessible thereto, certain of said lines arranged in groups and others as individual lines, means for operating said switch to extend connections to said lines when they are called either in local, incoming or enquiry calls, a relay in said switch operated to transmit a busy signal whenever said switch is operated to a busy one of said individual lines, said relay having means effective when said switch is operated to a group of said lines for preventing said relay from operating while the switch is testing the lines of said group and for causing said relay to operate, thereby to transmit said signal, only when all of the lines in said group are found busy, and means for at times operating said relay over a called line after a call has been extended to that line by said switch thereby to hold said call and control the extension of another call from said line.

7. In a telephone system, an automatic switch, lines accessible thereto, certain of said lines arranged in groups and others as individual lines, means for operating said switch to extend connections to said lines when they are called either in local, incoming or enquiry calls, a relay in said switch operated to transmit a busy signal whenever said switch is operated to a busy one of said individual lines, said relay having means effective when said switch is operated to a group of said lines for preventing said relay from operating while the switch is testing the lines of said group and for causing said relay to operate, thereby to transmit said signal, only when all of the lines in said group are found busy, and means for at times operating said relay over a called line after a call has been extended to that line by said switch thereby to control the transfer of said call to another line.

FRANZ SIMON.
